US00D941342S

(12) **United States Design Patent** (10) **Patent No.:** **US D941,342 S**
Protzman et al. (45) **Date of Patent:** **** Jan. 18, 2022**

(54) **DISPLAY SCREEN OR PORTION THEREOF WITH GRAPHICAL USER INTERFACE**

(71) Applicant: **Lutron Technology Company LLC**, Coopersburg, PA (US)

(72) Inventors: **Brent Protzman**, Easton, PA (US); **Michelle L. Greene**, Bethlehem, PA (US); **Erica L. Clymer**, Northampton, PA (US); **Jennifer Wong**, Breinigsville, PA (US); **Samuel F. Chambers**, Gwynedd Valley, PA (US); **Laura Marie Friedlander**, Harleysville, PA (US); **Edward J. Blair**, Telford, PA (US); **Stephen Lundy**, Coopersburg, PA (US); **John N. Callen**, Center Valley, PA (US)

(73) Assignee: **Lutron Technology Company LLC**, Coopersburg, PA (US)

(**) Term: **15 Years**

(21) Appl. No.: **29/801,717**

(22) Filed: **Jul. 30, 2021**

CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design. The interior dashed broken lines illustrate portions of the graphical user interface which form no part of the claimed design. The faded portions within the interior dashed broken lines form no part of the claimed design.
